UNITED STATES PATENT OFFICE.

ERNEST B. MILLER, OF BALTIMORE, MARYLAND, ASSIGNOR TO THE SILICA GEL CORPORATION, OF BALTIMORE, MARYLAND, A CORPORATION OF MARYLAND.

METHOD OF OBTAINING SWEET DOCTOR TEST.

Application filed November 10, 1924. Serial No. 749,016.

The present invention relates to a method of treating light petroleum distillates such as gasoline, kerosene, etc.

At the present time, it is customary to 5 include in the specification of a refined petroleum product such as gasoline or kerosene the requirement that the product be sweet to the doctor test (sodium plumbite).

After a petroleum product has been refined by treatment with a porous adsorbent 10 material like silica gel, in some cases a positive doctor test is obtained, that is to say, there is a visible reaction when the product is mixed with some of the doctor solution.

15 It is the object of the present invention to provide an improved process whereby the product obtained by refining with a porous body like silica gel is "sweet" to the doctor test, that is to say, there is no visible 20 action when the product is mixed with the doctor solution.

Referring to the drawings:

Fig. 1 is a plan view of a device for treating light petroleum distillates in accordance with the present invention;

Fig. 2 is a section taken substantially on the line 2—2 of Figure 1;

Fig. 3 is a vertical sectional elevation through another form of apparatus for 30 treating the distillates in accordance with this invention.

The so-called doctor test consists in shaking about two volumes of the product being treated with one volume of the doctor solution. The doctor solution is made from 35 sodium hydroxide and litharge (Pbo) in the proportions of about 125 grams of the sodium hydroxide in one liter of distilled water and 60 grams of the litharge. If 40 there is any visible reaction between the product and the solution, the test is said to be "sour" or positive. If there is no visible reaction, the test is said to be "sweet" or negative.

45 This test is supposed to indicate whether or not any substantial amounts of free acid or certain sulphur compounds are present. A peculiar phenomenon relative to petroleum products refined by a porous material 50 like silica gel is that although more sulphur is removed than by chemical methods of refining, the refined product in some cases is not "sweet" or negative when subjected to the doctor test.

55 According to the present invention, it is

found, if the refined product is subjected to actinic rays, for example, sunlight or rays from a mercury vapor lamp, a sweet product is obtained when subjected to the doctor test.

In refining light petroleum distillates with a porous body like silica gel, the oil being refined is brought in contact with the porous adsorbent, whereupon substances in solution like sulphur compounds are adsorbed 60 in the pores of the adsorbent. Thereafter the adsorbent is revivified or activated so that it may again be used to treat more oil.

According to the present invention, the refined product discharged from the refining 70 apparatus is exposed to actinic rays. The length of time of the exposure depends on the condition of the refined product, the intensity and wave length of the rays, and the thickness of the layer of oil being treated.

75 In view of these four variables, it is difficult to give a definite statement as to the length of the exposure. To illustrate, however, one hundred cubic centimeters of straight run kerosene refined with silica gel 80 by the Vacuum Oil Company which gave a "positive" doctor test was placed in a white porcelain tray 5 inches by 8 inches at a distance of 9 inches from the light bulb of a 700 watt quartz mercury vapor lamp. It 85 was removed after five seconds exposure and gave a "negative" doctor test. If exposed for too long a time the oil is likely to be discolored and this naturally, is to be avoided.

To carry out this treatment, the conduit through which the refined oil discharged from the refining plant is flowing may be enlarged into a wide thin passage, the cross section of which is substantially rectangular 95 in outline and the height of which is very small so that the oil is flattened out into a wide thin layer. Suitable actinic rays are directed either on the top or bottom, or both, of this flattened passage, the walls of the 100 passageway being transparent.

A device of this kind is shown in Figures 1 and 2. The conduit A is connected with a flattened casing B which may be of the form shown in Figures 1 and 2 and has 105 transparent top and bottom walls. Sources C of actinic rays may be disposed either above or below the casing B, or both above and below as shown.

The light petroleum distillate discharged 110

from the silica gel refining plant flows through the conduit A and casing B and is discharged at D. The rate of flow through the casing B may be controlled by a valve E in the conduit A so that the distillate will be subjected to the actinic rays for the proper length of time to render the distillate "sweet" to the doctor test. Another form of device for subjecting the distillates to actinic rays is illustrated diagrammatically in Figure 3. A source G of actinic rays is disposed adjacent the center of a casing H. The interior of this casing is provided with a series of baffle plates J which extend inwardly to adjacent the source of actinic rays. The inner ends of these baffle plates however are spaced slightly from the source of actinic rays, thereby providing a passage between said source of rays and the inner ends of the baffle plates. Another series of baffle plates K alternate with the baffle plates J and are disposed so there is no passage between their inner ends and the source of rays but their outer ends are spaced from the casing thereby forming narrow passageways at their outer ends. The distillate that has been refined by the silica gel process enters through the conduit L and then is divided by one of the baffle plates K, a portion going to the right therefore and the remainder to the left. The portion that flows to the right, because of the baffle plates K and J, is caused to move inwardly toward the source of rays and then

around the inner edge of baffle plate J, then outwardly and around the outer end of baffle plate K, and then inwardly, and around the inner end of the next baffle plate J and finally discharged through the outlet M. The portion of the distillate that flows to the left moves through a similar path. In this way the distillate is more or less agitated and given a very thorough treatment by the rays. The rate of flow through the casing may be controlled by a valve N.

Having thus described my invention, what is claimed as new and desired to be secured by United States Letters Patent is:

1. The method of rendering sour light petroleum distillates, which have been refined by treatment with a porous adsorbing material, "sweet" to the doctor test, consisting in exposing the product thus refined to actinic rays.

2. The method of rendering sour light petroleum distillates, which have been refined by treatment with silica gel, "sweet" to the doctor test, consisting in exposing the product thus refined to actinic rays.

3. The method of rendering a "sour" light petroleum distillate "sweet" to the doctor test, which consists in refining such distillate by treatment with a porous adsorbing material and thereafter exposing it to actinic rays.

In testimony whereof I hereunto affix my signature.

ERNEST B. MILLER.
